Inventor.
B. E. Colley.

United States Patent Office.

B. E. COLLEY, OF BOSTON, MASSACHUSETTS.

Letters Patent No. 96,204, dated October 26, 1869.

PIANO-FORTE ACTION.

The Schedule referred to in these Letters Patent and making part of the same.

To all persons to whom these presents shall come:

Be it known that I, B. E. COLLEY, of Boston, in the county of Suffolk, and State of Massachusetts, have invented certain new and useful Improvements in Piano-Forte Actions; and that the following is a full and exact description of the same, reference being had to the accompanying plate of drawings.

The present invention relates to that class of piano-forte actions in which is employed a jack, arranged to escape when actuated by the key-lever, to which it is pivoted or hung, in any suitable manner, directly from a but on the hammer-stem, by a movement or play toward its centre of motion, said jack being provided with an arm, extending along and over the key-lever toward its rear or inner end, where the back-catch is located or fixed, with such arm, at or near its outer end, arranged through a cloth or other proper cushion suitably applied to rest upon the key-lever; and

This invention consists in interposing between the said back-arm of the jack and the hammer-stem, at a point back of that where the movement and escape of the jack-fly from the hammer-stem but occur, a detached connection, by either attaching the same wholly to the hammer-stem or to the said jack, or partially to both, and suitably protected against noise, and in such manner that by and through it, in the ordinary operation of the action, the hammer-head, through its stem, shall come to a rest upon the jack, back of its fly, the instant the back-catch commences to relieve from the tail of hammer-head, whereby a most perfect and certain "repeat," at almost any and all positions of the key-lever, is secured, for the obvious reason, that by such relative position of the hammer-head, or its stem, upon the jack, not only can another blow be almost if not wholly given, but great assistance afforded, and vigor, quickness, and rapidity given to the motion of the jack, to resume or come into its position under the hammer-stem but, from which, in its previous action, it had escaped.

In the accompanying plate of drawings, my improvements in piano-forte actions are illustrated—

Figure 1 being a side view or elevation of the same, with the several parts composing the same in their normal position, and some in whole or partial longitudinal section, and

Figure 2, also a side view or elevation, but showing the relative position of the parts composing the action, at the moment the relief of the back-catch from the tail-piece of hammer-head commences.

A, in the drawings, represents a key-lever, which is arranged in the ordinary manner, turning upon a pin, B, as a centre, fixed in key-board C, at the proper point.

C², the rear or inner end of key-lever, near which end the mechanism for imparting motion to a suitable hammer-head is arranged, as will be now explained.

D, an arm, similar to the key-arm of a jack in a "French action," so called, and

E and F, screws, passing through said arm D into key, the one for adjusting the height of its end G from the key-lever, and the other for fastening or holding it in such position adjusted.

At the said end G of arm D, to a transverse pivot, a, thereof, is hung a jack-frame, H, having an upright or vertical fly-piece, I, and rigid block or standard J back thereof, at a short distance therefrom.

K, a screw-rod, passing loosely through fly-piece I of jack, and screwing into standard J, on which screw-rod are nuts or washers L and M, one on each side of fly, bearing against the same, by means of which, as the said rod is screwed into or out of the standard, the fly-piece is forced toward or away from the same, as and for the purpose to be hereinafter stated.

N, an arm, forming a part of jack-frame, and extending back therefrom along and over the key-lever, toward its rear or inner end C², at which the back-catch O is fixed and located. This arm, at its outer end P, when the action is at rest, bears through a cushion, b, applied thereto, or to the key-lever, at the proper point upon the key-lever, as shown in fig. 1.

Q, a hammer-head, attached to one end of stem R, that, at its other end, terminates in a but-piece, S, hung by a pivot, e, in and between the arms of a bifurcated flange, T, secured by a screw, U, to a rail, V.

By the flat or smooth surface W of but-piece S, the hammer-stem rests upon the upper end X of fly-piece to jack-frame H, the proper position of the jack-fly under the same, being regulated by and through the screw K, having nuts, hereinabove referred to, and its height by means of the screws E and F to the key-arm of jack, also hereinbefore referred to.

This but-piece S, just in front of the point of contact, between it and the jack-fly, is notched or cut out, as shown at Y, and in such notch, as well as along its surface W, pieces of cloth or leather are applied to deaden and prevent any and all noise by friction, or otherwise, in the operation of the action.

Z, a stem, fixed in upper end of block J to jack-frame, and extended upward therefrom toward hammer-stem, in a direction slightly inclined thereto.

A², a block, pad-head, or button, applied to upper end of stem Z, by screwing the same thereon, which allows of its adjustability and regulation, as is obvious.

B², a cushion on hammer-stem, and at a point thereof to prevent noise between the stem and block A² in the operation of the action.

C², a block, cushioned or protected with cloth, and located just in front of cushion B², hereinabove referred to, on the under side of hammer-stem but S.

Through this block C², the hammer-stem comes to a rest on the block A² of jack-frame, at the moment the back-catch commences to relieve itself from the

tail-piece D² of hammer-head, after a movement of the action through the key-lever to produce a blow by the hammer-head upon the string or strings of the instrument properly and relatively arranged therefor.

The operation of the action hereinabove described is as follows:

The key-lever, at its finger-end, being depressed and held, the hammer-head, through the jack-frame, is sent upward to the strings with a force corresponding thereto, when the fly to jack, escaping from the but of stem by passing over the corner F² thereof into its notch, the hammer-head falls back, and is caught by the back-catch, as in common piano-actions.

By now raising the finger from the key, the key is left free to resume its normal position, or at least to commence moving thereto, at which instant the back-catch begins to relieve from the hammer head, which, by its stem through the block A², then immediately comes to a bearing upon the block of jack-frame, back of its fly, as shown in fig. 2, and thereby not only serves to assist the jack in bringing its fly into position under the hammer-stem but for another blow, but establishes at such time, as it were, another connection between the key and the hammer-stem, by means of which, in combination with what movement the jack-fly can give to the hammer-head, a blow there-

from is insured at any and almost all positions of the key-lever, consequently securing the utmost rapidity and perfectness of "repeat," as is manifest.

In lieu of the peculiar formation or construction and application of the detached connection between the hammer-stem and jack-frame, hereinabove described, the position of the parts may be reversed, and their forms changed, as, for instance, a curved arm, such as shown in fig. 3, interposed and arranged as there shown, and in many other obvious ways and forms, the operation and effect in each case being the same.

Having thus described my improvements, I shall state my claim as follows:

What I claim as my invention, and desire to have secured to me by Letters Patent, is—

In the class of piano-actions above described, a detached connection between a hammer-head, through its stem or part attached thereto, arranged or located inside of the point of motion and escape of the jack, and the jack-frame, or any suitable part thereof, for operation, substantially as described, and for the purpose specified.

B. E. COLLEY.
